UNITED STATES PATENT OFFICE.

THOMAS FISHER, OF DESLOGE, MISSOURI, ASSIGNOR OF ONE-THIRD TO
JOHN N. SHANNON, OF DESLOGE, MISSOURI.

DUMPING AND CAGING APPARATUS FOR MINE-CARS.

No. 827,354.

Specification of Letters Patent.

Patented July 31, 1906.

Application filed September 29, 1905. Serial No. 280,691.

To all whom it may concern:

Be it known that I, THOMAS FISHER, a citizen of the United States, and a resident of Desloge, St. Francois county, Missouri, have invented certain new and useful Improvements in Dumping and Caging Apparatus for Mine-Cars, of which the following is a specification containing a full, clear, and exact description, reference being had to the accompanying drawings, forming a part hereof.

My invention relates to a dumping and caging apparatus for mine-cars.

The object of my invention is to provide a simple apparatus utilizing fluid-pressure and requiring but a single attendant and adapted to dump mining-cars at the top of a mine-shaft and to cage loaded cars at the bottom of the shaft.

To the above purposes my invention consists in certain novel features of construction, which will be hereinafter more clearly set forth, pointed out in my claims, and illustrated in the accompanying drawings, in which—

25 Figure 1 is a vertical section showing my improved apparatus in use for dumping a car at the top of a mine-shaft. Fig. 2 is a longitudinal section taken through the center of the cylinder of my improved apparatus and 30 the pivoted beam that carries said cylinder. Fig. 3 is an enlarged vertical section taken on the line 3 3 of Fig. 1. Fig. 4 is an enlarged horizontal section taken on the line 4 4 of Fig. 1. Fig. 5 is an enlarged horizontal section taken on the line 5 5 of Fig. 3 and showing the four-way valve I make use of in carrying out my invention.

Referring by numerals to the accompanying drawings, 1 1 indicate the vertical timbers that surround the mine-shaft; 2, the cage that is elevated and lowered in the usual manner by the cable 3 and which carries the mine-car 4.

45 5 indicates a platform on which the operator of my improved apparatus stands, and 6 indicates the tilting platform which receives the car while it is being dumped. Extending upwardly from the platform 5 a short distance to one side of the space occupied by 50 the cage 2 is a pair of vertically-arranged timbers 7, that extend to the roof 8, which is arranged over the platform.

All of the parts just mentioned are of ordi-

nary construction and form no part of my invention.

Pivotedly arranged between the timbers 7 upon a horizontal shaft 9 or in any suitable manner is a beam 10, the forward end of which extends to a point immediately over the position normally occupied by the car 4 60 when it is positioned on the cage 2. Suspended beneath this timber 10 by means of suitable hangers 11 is a cylinder 12, the forward end of which is closed by a head 13 and the rear end being closed by a cap 14. Arranged to operate in this cylinder is a piston 15, and secured thereto in the usual manner is the rear end of a piston-rod 16, which extends through a suitable stuffing-box 17 on the head 13, and the forward end of said rod 70 carries an inverted-U-shaped hook 18. The inner face of the rear depending member of this hook is transversely corrugated, as indicated by 19.

Discharge-cocks 20 are arranged on the 75 under side of the cylinder 12 at each end thereof for the purpose of allowing for the discharge of any water of condensation or excess of oil that might accumulate within the cylinder.

Extending outwardly from the right-hand one of the posts 7 is a bracket 21, on top of which is arranged a four-way valve 22, that is manipulated by a handle 23. Leading into one side of this four-way valve is an inlet-pipe 24, in which is located a suitable inlet-valve 25. Leading from the opposite side of the four-way valve downwardly through the bracket 21 is an exhaust-pipe 26. Leading from the sides of the four-way valve are 85 pipes 27, in which are located suitable regulating-valves 28. The ends of these pipes 27 terminate adjacent the right-hand one of the posts 7, and to said pipes are fixed in any suitable manner the inner ends of suitable 95 flexible tubes 29. These flexible tubes extend to the ends of the cylinder 12, and their outer ends are fixed in any suitable manner to short pipes 30, one of which enters the side of the cap 14 and the opposite one entering the side of the cylinder 12, adjacent the head 13. The connections just described are for the purpose of alternately allowing fluid-pressure to discharge into the ends of the cylinder 12 to move the piston 15 backwardly and forwardly therein.

Secured to the top of the beam 10 a short distance from the front end thereof is a loop 31, to which is attached the lower end of a chain 32. The upper end of this chain is secured to the lower end of a rod 33, that extends upwardly through a timber 34, carried by the roof 8 and there being a nut 35 located on the upper end of said rod. An expansive coil-spring 36 is positioned on the rod 33 between the timber 34 and the nut 35, which coil-spring is of sufficient tension to yieldingly maintain the beam 10 and parts carried thereby in an approximate horizontal position.

When my improved apparatus is positioned for dumping mine-cars at the top of a shaft, the beam and cylinder are arranged at such a height as that when a car is brought by the cage into a position where it can be moved onto the dumping-platform 6 the upper edge of the rear wall of the car 4 occupies a position between the depending jaws of the hook 18, the piston 15 at this time being at its rearward limit of movement.

The operator of my improved apparatus is stationed at the right-hand side of the beam and cylinder and adjacent the bracket 21. To bring the apparatus into operative condition, the valve 25 is opened and suitable fluid-pressure passes through the inlet-pipe to the four-way valve 22. This valve has been so manipulated as that the fluid-pressure will pass through the tubular connections 27, 29, and 30, that lead to the front end of the cylinder, and thus said pressure is delivered to a point in front of the piston 15. This action maintains the piston 15, piston-rod 16, and inverted U-shaped hook 18 at their rearward limit of movement, said hook being adapted to engage the rear wall of the car 4. When the car has been brought to the proper height by the cage and it is desired to dump said car, the operator reverses the position of the four-way valve and allows the fluid pressure to pass from the pipe 24 through the tubular connections 27, 29, and 30, leading to the rear end of the cylinder. Thus the pressure is applied to the front side of the piston, and as a result said piston, piston-rod, and hook 18 carried thereby are moved forwardly and the car is pushed off from the cage 2 onto the dumping-platform 6, and as said platform tilts the contents of the car are discharged onto a screen or chute. The hook 18 during this operation maintains its position on the upper edge of the rear wall of the car, and the cylinder 12 swings or rocks vertically with the beam 10 upon its pivot to accommodate any change of elevation of the rear end of the car. To accommodate this vertical movement of the cylinder and beam, the flexible pipes 29 are provided between the pipes 27 and 30. After the car has thus been dumped the operator moves the four-way valve back to its normal position, which allows the fluid-pres-

sure to discharge into the forward end of the cylinder and move the piston, piston-rod, and the hook 18 carried thereby rearwardly, and thus return the car 4 onto the cage 2.

Whenever the piston moves within the cylinder 12, the exhaust from said cylinder will discharge through the corresponding tubular connections 30, 29, and 27, through the four-way valve 22, and out through the exhaust-pipe 20. Thus the two sets of tubular connections 27, 29, and 30 are alternately inlet and exhaust pipes.

The regulating-valves 28 can be adjusted and set so as to admit just the proper amount of fluid-pressure required for moving the piston forwardly and backwardly in the cylinder 12.

An apparatus constructed in accordance with the foregoing description is simple, strong, and durable, can be operated with any fluid-pressure and by a single operator, and can be advantageously used for dumping cars at the top of the shaft or caging cars at the bottom of a shaft.

I claim—

1. In an apparatus of the class described, a guide arranged to swing vertically, a member arranged to move horizontally in said guide, and a car-engaging member carried by the horizontally-moving member; substantially as specified.

2. In an apparatus of the class described, a guide arranged to swing vertically, a rod arranged to move horizontally in said guide, a car-engaging hook carried by one end of said rod, and means whereby the rod is moved in said guide; substantially as specified.

3. In an apparatus of the class described, a cylinder pivoted to swing vertically, a piston in said cylinder, a piston-rod carried by the piston, a car-engaging hook fixed at one end of the piston-rod, and means whereby fluid-pressure is admitted to each end of the cylinder; substantially as specified.

4. In an apparatus of the class described, a horizontally-moving member operating in the same horizontal plane with the top of the car to be dumped, and a car-engaging hook carried by the forward end of the horizontally-moving member and adapted to engage the top of the car to be dumped; substantially as specified.

5. In an apparatus of the class described, a guide horizontally arranged in the same horizontal plane with the top of the car to be dumped, a horizontally-moving member operating in said guide, a car-engaging member carried by said horizontally-moving member, and adapted to engage the top of the car to be dumped, and means whereby motion is imparted to the horizontally-moving member; substantially as specified.

6. In an apparatus of the class described, a horizontally-moving member held to oper-

ate in the same horizontal plane with the top of the car to be dumped and which member is arranged to swing vertically, and a car-engaging member carried by the forward end of the horizontally-moving member; substantially as specified.

5 In testimony whereof I have signed my

name to this specification in presence of two subscribing witnesses.

THOMAS FISHER.
